UNITED STATES PATENT OFFICE.

WILLIAM H. EYNON AND DAVID DUCKETT, OF CLEVELAND, OHIO.

GAME APPARATUS.

SPECIFICATION forming part of Letters Patent No. 655,768, dated August 14, 1900.

Application filed April 25, 1899. Serial No. 714,406. (No model.)

To all whom it may concern:

Be it known that we, WILLIAM H. EYNON and DAVID DUCKETT, residing at Cleveland, in the county of Cuyahoga and State of Ohio, 5 have invented a new and useful Game Apparatus, of which the following is a specification.

Our invention is in the nature of an apparatus with which to play a game which we 10 designate the game of "time," the object of the invention being to provide an interesting, amusing, and instructive parlor-game for children.

With this object in view our invention consists in the improved construction, arrangement, and combination of parts hereinafter 15 fully described, and afterward specifically pointed out in the appended claim.

In order to enable others skilled in the art 20 to which our invention most nearly appertains to make and use the same, we will now proceed to describe its construction and operation, reference being had to the accompanying drawings, forming part hereof, in 25 which—

Figure 1 is a top plan view of a game apparatus constructed in accordance with our invention. Fig. 2 is a vertical longitudinal section through the same.

Like letters of reference mark the same parts 30 in both figures of the drawings.

Referring to the drawings by letters, A indicates an oblong rectangular board or card in the center of which is erected an arbor or 35 shaft B, upon which are journaled four sets of hands, being four minute-hands C, D, E, and F, and four hour-hands C', D', E', and F', the portion of the board over which the hands may be rotated being painted to represent a 40 clock-face. Near the four corners of the board are four dials C'', D'', E'', and F'', each being provided with a pintle or arbor at its center, upon which is swiveled loosely an arrow-hand, as at c, d, e, and f. The four 45 sets of hands at the clock-face are of different colors, and the four hands of the corner-dials are correspondingly colored. In practice the hands are intended to be colored red, green, yellow, and white and are marked

"R," "G," "Y," and "W" to indicate these 50 different colors.

The four corner-dials are divided into twenty spaces each and numbered from "1" to "10," with blank spaces or spaces marked "0" intervening.

55

The game as illustrated is played by four persons, each of which has a corner-dial and the correspondingly-colored set of clock-hands as his own. The players in succession spin or twirl the arrow-hands on the corner-dials, and when the hand has stopped the number indicated shows the number of spaces the player is entitled to move the minute-hand of corresponding color on the clock-dial. When a minute-hand has been moved 60 sixty spaces, the hour-hand of corresponding color is moved from "XII" to "I" on the clock-dial and the game continued until one player has moved his set of clock-hands the number of hours and minutes previously agreed 65 upon as the limit of the game, when he is declared the winner. The game may be continued, if desired, until all but one player is out.

The game will prove very interesting and 70 amusing to children and will instruct them in the movement of the hands of a clock, whereby they may be taught to tell the time.

As many players may be provided for as is desired by increasing or diminishing the number of sets of hands on the clock-dial, and for this reason the spindle or arbor B is made removable, being secured by a nut B', sunk flush with the under surface of the board.

When a hand on any of the corner-dials 85 stops over a blank or zero space, the player is not entitled to move his minute-hand.

It will be readily understood that the arrangement of the dials may be changed—such, for instance, as by placing the clock-face and its hands in a different part of the board—and the shape of the hands or the ornamentation of the dials varied without departing from the spirit and scope of our invention.

Having thus fully described our invention, what we claim as new, and desire to secure by Letters Patent of the United States, is—

95

A game apparatus comprising a board provided with a clock-dial, a shaft or arbor removably fixed in the center thereof and a plurality of differently-colored sets of hour and minute hands loosely mounted on the shaft, and a series of graduated dials corresponding in number with the sets of hands and having swiveled arrow-hands colored to cor-

respond with the sets of hands, substantially as described.
